UNITED STATES PATENT OFFICE.

GEORGE W. RICHARDSON, OF PLANO, ILLINOIS.

DEVICE FOR CONVERTING MOTION.

SPECIFICATION forming part of Letters Patent No. 338,780, dated March 30, 1886.

Application filed July 8, 1885. Serial No. 170,966. (Model.)

To all whom it may concern:

Be it known that I, GEORGE W. RICHARDSON, a citizen of the United States, residing at Plano, in the county of Kendall and State of Illinois, have invented certain new and useful Improvements in Devices for Converting Motion; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

15 My present invention relates to improvements in devices for converting rectilinear into curvilinear motion; and it consists in certain novel features of construction, combination, and arrangement hereinafter described 20 and claimed.

In the drawings, Figure 1 is a plan view with the cap-piece removed. Fig. 2 is a side elevation, partly in section. Fig. 3 is a detail view of the cap-piece, and Fig. 4 shows a 25 modification.

A is the operating-handle, secured to the ring B in the ordinary manner.

C is a cap-piece centrally apertured to fit over a lug, g, projecting upward from the face 30 of the cam D and placed on the ring B, and secured in place by an annular flange of the block d, which latter rests on the lug g and is secured thereto by a screw or bolt, d'. The said cap-plate is free to turn about the lug g 35 of the cam-wheel in either direction, to shift the position of the binding-roller, for the purpose hereinafter set forth.

The cap-piece C is provided with two pairs of depending arms, E E, placed opposite each 40 other, as shown. Between the pairs of arms E, I place the double wedges F F, the purpose of which will presently appear.

The cam-wheel D is made of the peculiar shape shown, being elliptical in longitudinal 45 horizontal section and rectangular in cross-section.

A flat double spring, G, or its equivalent, is secured to the cam-wheel D, and holds the cap-piece C in position in the operation of the 50 device. The long diameter of the cam-wheel D is about equal to the inner diameter of the ring B, while the short diameter is equal to

slightly more than one-half the same. Between the ring B and the cam-wheel D, on the opposite sides of the said wheel, I place 55 the rollers H H. The depending arms E E fit around these rollers and change the position of the same in the operation of the device.

In the drawings I have shown the cam-wheel D formed on the end of a screw-driver or auger 60 handle; but it can be formed on the end of a drive-shaft or in any other place where it can be used advantageously.

In Fig. 4 I have shown instead of the double flat spring G two coiled springs, I I, supporting a flat plate, J. Either the double flat spring or the two coiled springs may be used with equally good results.

In operation, the cap-piece C, being turned in one or the other direction, will cause the 70 depending arms E E to carry the rollers in opposite directions toward the ends of the spaces between the ring B and the cam-wheel D, to cause the ring to bind in either direction, thereby making the device either right 75 or left handed in its operation, as is manifestly apparent. The rollers will bind between the ring B and the cam-wheel D when the handle is moved in one direction, and will cause the cam-wheel to travel in the same 80 direction as the ring B. As the ring is brought back in the opposite direction, it will slip over the rollers and impart no motion to the cam-wheel. It will thus be seen that the reciprocating motion of the ring B is converted into 85 the circular motion of the cam-wheel.

The double flat spring G or the flat plate J, acting on the double wedge F, holds the cap-piece to any desired position.

Having thus described my invention, what I 90 claim, and desire to secure by Letters Patent, is—

1. The combination, with a ring and a concentric cam-wheel, of intermediate binding-rollers, and a cap, the latter provided with 95 means to shift the position of said rollers, whereby the parts may be caused to interlock in either direction, substantially as and for the purposes set forth.

2. The combination, with the cam-wheel 100 having an upwardly-projecting stud, a concentric ring, and intermediate binding-rollers, of a centrally-apertured cap-plate mounted on said stud and provided with depending arms

arranged in opposite pairs and free to turn around said stud, to shift the position of the rollers in either direction, and interlocking mechanism, substantially as described, to secure the cap-plates in either of its adjusted positions, as and for the purposes specified.

3. The combination, with the ring B, provided with a suitable handle, of the cam-wheel D, the intermediate locking-rollers H, spring-plate G, and the cap-plate C, provided with

the depending pairs of arms E and the double wedges F, all constructed, arranged, and operating substantially as shown and described.

In testimony whereof I affix my signature in presence of two witnesses.

GEORGE W. RICHARDSON.
